Primary Examiner—Nelson C. Holtje
Attorney, Agent, or Firm—Pendorf & Cutliff[57] **CLAIM**

The ornamental design of a clock face, as shown and described.

DESCRIPTION

FIG. 1 is a front elevational view of a clock face. The clock face is conventionally of no appreciable thickness and the rear is flat and unornamented. The three hands and the lunar/solar symbols shown in broken-lines are for illustrative purposes only and form no part of the claimed design.
